FIG. 1 is a three-quarter front perspective view, looking downwardly, showing a patio room embodying my new design;

FIG. 2 is a three-quarter perspective view, on a slightly enlarged scale, showing the opposite end of the patio room of FIG. 1;

FIG. 3 is an interior perspective view, on a further enlarged scale, looking toward one inside corner of the patio room of FIG. 1;

FIG. 4 is a similar interior perspective view, but looking toward the opposite inside corner of the patio room of FIG. 1;

FIG. 5 is a three-quarter front perspective view, similar to FIG. 1, but showing a patio room embodying my new design and having a variation in the upper outside panels, with a view similar to FIG. 2 having a corresponding variation; and

FIG. 6 is an interior perspective view of the patio room of FIG. 5, similar to FIG. 4 but showing a variation in

the upper beams, with a view similar to FIG. 3 having a corresponding variation.

The rear of the patio room is open, but may abut an existing building.

I claim:

The ornamental design for a patio room, as shown and described.
